(57) **CLAIM**

The ornamental design for an orthotic device, as shown and described.

DESCRIPTION

FIG. 1 is a perspective view of an orthotic device showing our new design;

FIG. 2 is a first side elevational view thereof;

FIG. 3 is a top plan view thereof;

FIG. 4 is a bottom plan view thereof;

FIG. 5 is a second side elevational view thereof;

FIG. 6 is a rear elevational view thereof; and,

FIG. 7 is a front elevational view thereof.

The broken line showing of the rectangular shapes on the top surface of the orthotic device in FIGS. 1, 2, 5, and 7 is included for the purpose of illustrating only and forms no part of the claimed design.
